CLAIM

The ornamental design for safety needle, as shown and described.

DESCRIPTION

FIG. 1 is a front view of the safety needle in the closed configuration, with removable protective sleeve removed from the needle shaft.

FIG. 2 is a rear view of the safety needle in the closed configuration, with removable protective sleeve removed from the needle shaft.

FIG. 3 right side view of the safety needle in the closed configuration, with removable protective sleeve removed from the needle shaft.

FIG. 4 is a left side view of the safety needle in the closed configuration, with removable protective sleeve removed from the needle shaft.

FIG. 5 is a bottom view of the safety needle in the closed configuration, with removable protective sleeve removed from the needle shaft.

FIG. 6 is top view of the safety needle in the closed configuration, with removable protective sleeve removed from the needle shaft.

FIG. 7 is a front isometric view of the safety needle in the closed configuration, with removable protective sleeve removed from the needle shaft.

FIG. 8 is a front view of the safety needle in the open configuration, with removable protective sleeve removed from the needle shaft.

FIG. 9 is a rear view of the safety needle in the open configuration, with removable protective sleeve removed from the needle shaft.

FIG. 10 is left side view of the safety needle in the open configuration, with removable protective sleeve removed from the needle shaft.

FIG. 11 is a right side view of the safety needle in the open configuration, with removable protective sleeve removed from the needle shaft.

(Continued)

FIG. 12 is a top view of the safety needle in the open configuration, with removable protective sleeve removed from the needle shaft.

FIG. 13 is a bottom view of the safety needle in the open configuration, with removable protective sleeve removed from the needle shaft; and,

FIG. 14 is an isometric left side view of the safety needle in the open configuration, with removable protective sleeve removed from the needle shaft.

Any features shown in broken lines in the figures form no part of the claimed design.
